CLAIM

The ornamental design for a holder for wine bottle and the like, as shown and described.

DESCRIPTION

FIG. 1 is a front elevational view of the holder for wine bottle and the like showing my new design;

FIG. 2 is a right side elevational view thereof, the opposite being identical;

FIG. 3 is a top plan view thereof;

FIG. 4 is a bottom plan view thereof;

FIG. 5 is a rear elevational view thereof; and,

FIG. 6 is a fragmentary sectional right side elevational view thereof with the bottle shown in broken lines for illustrative purposes only.

FIG. 1

FIG. 2

FIG.5

FIG.4

FIG.3

FIG. 6
